His Attorney

UNITED STATES PATENT OFFICE.

THOMAS H. STULTS, OF JOPLIN, MISSOURI.

RAIL AND CHAIR FOR HOLDING SAME.

1,322,841.

Specification of Letters Patent. Patented Nov. 25, 1919.

Application filed April 26, 1919. Serial No. 292,868.

To all whom it may concern:

Be it known that I, THOMAS H. STULTS, a citizen of the United States, residing at Joplin, in the county of Jasper and State 5 of Missouri, have invented a certain new and useful Improvement in Rails and Chairs for Holding Same, of which the following is a specification.

My invention relates to improvements in 10 rails and chairs for holding same.

One of the objects of my invention is to provide a rail which is cheap to manufacture, which is strong and which can be used for a much longer period than the ordinary 15 rail. This object is achieved by providing the upper and lower edges respectively of the rail with two balls, each adapted to support travel and each adapted to serve as the base of the rail, said edges being reversible in position, so that when one ball 20 becomes too worn for use as a support for the car wheels, the rail may be reversed and the worn ball be employed as the base of the rail.

25 My invention provides further a novel chair which is arranged to support and clamp either ball of my improved rail.

My invention provides still further a rail chair of novel construction, which is provided with means of adjustment so as to be 30 adapted to hold rails of different widths.

The novel features of my invention are hereinafter fully described and claimed.

In the accompanying drawing which illustrates the preferred embodiment of my invention,

Figure 1 is a cross section of my improved rail and rail chair, shown in operative relationship to each other.

40 Fig. 2 is a perspective view of my improved rail and two of my improved rail chairs.

Fig. 3 is a horizontal sectional view on the line 3-3 of Fig. 1.

45 Fig. 4 is a side elevation, enlarged, of a portion of my improved rail.

Fig. 5 is a perspective view of one of the chair members.

Similar reference characters designate 50 similar parts in the different views.

1 designates the web of my improved rail, and 2 the two balls of the rail connected by said web. The balls 2 are alike in cross section and are each arranged to support 55 the usual travel of car wheels thereon, and

each is adapted to serve as the base of the rail.

My improved rail chair comprises a member 3, which is provided with a seat 4 adapted to receive and support either of 60 the balls 2, and a clamping wedge member 5 which is adapted to clamp the adjacent side of either ball 2 and which is provided with an upwardly extending arm 6 adapted to clamp the adjacent side of the web 1 and 65 which is provided with one or more horizontal longitudinal slots 7 adapted to receive bolts 8 which extend through vertical slots 9 in the web 1. Said bolts 8 also extend through transverse holes 10 provided in an upwardly 70 extending arm 11 on the member 3. The arm 11 is adapted to clamp the adjacent side of the web 1 and the holes 10 are disposed in register with the slots 9 and 7.

The bolts 8 are provided respectively with 75 nuts 12 which bear against the arm 6.

The outer side of the member 5 is provided with an inclined surface 13 disposed at an angle to the web 1 and which is adapted to fit against a similarly inclined surface 80 14 provided at the inner side of an upwardly extending arm 15 provided on the upper side of the member 3. As shown in Fig. 1, the arm 15 is provided with a longitudinal shoulder 16 adapted to fit in the 85 groove 17 provided in the member 5. This shoulder prevents the member 5 from any upward movement in the member 3.

As shown in Fig. 2, the rail chairs may be 90 of different lengths so as to receive one or more bolts, two widths of chairs being shown in this figure.

In the operation of my invention, the rail has one ball 2 mounted in the seat 4 of the 95 chair member 3, after which the chair member 5 is slipped endwise between the arm 15 and the web 1. The member 5 is driven tightly into engagement with the inclined surface 14 of the member 3 and with the web 1 and lower ball of the rail. The bolts 8 are 100 then inserted through the slots 7 and 9 and the holes 10, and the nut 12 mounted on the bolts so as to draw the arms 6 and 11 tightly against the web 1.

When the upper ball 2 has become too 105 much worn for further use, the nuts 12 are removed from the bolts 8, and the latter are withdrawn, following which the chair member 5 is driven in the reverse direction until freed from the chair member 3. The rail 110

may then be reversed in position, the worn ball 2 being mounted in the seat 4, following which the clamping member is driven into position and the bolts 8 and nuts 12 are applied, as already described.

By providing the vertical slots 9 in the web 1, provision is made for the lowering of the rail in the chair so as to compensate for the wear on the ball which now serves as the 10 base of the rail.

The longitudinal slots 7 are provided in the chair member 5, to permit of the longitudinal adjustment of said chair member, required by different thicknesses of rail or 15 by the reduction of thickness in the worn ball of the rail when such worn ball is used as the base of the rail.

I do not limit my invention to the structure shown and described, as modifications, 20 within the scope of the appended claims, may be made without departing from the spirit of my invention.

What I claim is:—

1. A rail having a web provided with a 25 vertical slot extending transversely therethrough, and a chair comprising two members, one of which is provided with a seat for receiving and supporting the base of the rail and having an arm adapted to clamp 30 said web, the arm having a transverse hole registering with said slot, the other member, having a horizontal slot registering with the first named slot, the last named member having an outer side inclined to said web so as 35 to serve as a wedge and which bears against the first named member, and a clamping bolt extending through said slots and said hole.

2. A reversible rail having at its upper 40 and lower edges respectively two balls, either of which is adapted to support travel, and a chair comprising a supporting member having a seat adapted to receive and support either of said balls and having an arm 45 adapted to clamp the web of the rail, the web being provided with a vertical slot extending transversely therethrough, said arm having a hole registering with said slot, a

clamping member adapted to clamp either of said balls and having an arm provided 50 with a horizontal slot registering with the first named slot, the first named member having at its inner side at the outer side of the rail, a surface inclined to the web of the rail, the second named member having 55 at its outer side a surface inclined to the web of the rail and fitted to the inclined surface of the other member, and clamping means extending through said slots and said hole and vertically adjustable in the first 60 named slot and horizontally adjustable in the second named slot and arranged to clamp said members to opposite sides of the web of the rail.

3. A rail chair comprising two members, 65 each having means for clamping the adjacent side of a rail, one of the members having a seat adapted to receive and support the base of a rail, one of said members having a transverse hole, the other member having a longitudinal slot registering with said hole, said slot and hole being adapted to receive therethrough a clamping bolt, one of said members being of wedge form and arranged to wedge between the rail and the 70 other member.

4. A rail chair comprising a member having means for receiving and supporting the base of a rail and having means for clamping the adjacent side of the web of the rail 80 and provided with a transverse hole, and having at its inner side a surface which is inclined to the web of the rail, and a clamping wedge member arranged to clamp the adjacent side of the rail and having a horizontal slot registering with said hole, and provided at its outer side with an inclined surface adapted to fit against the inclined surface of the other member, said slot and hole being adapted to receive therethrough 85 a suitable securing member for clamping said members to the rail.

In testimony whereof I have signed my name to this specification.

THOMAS H. STULTS.
